ATTORNEY

UNITED STATES PATENT OFFICE.

JOSEPH BYRNES, OF CHICAGO, ILLINOIS, ASSIGNOR OF TWO-THIRDS TO
JAMES STANSON AND JOHN HOLLOWED, OF SAME PLACE.

BOTTLE-STOPPER.

SPECIFICATION forming part of Letters Patent No. 282,953, dated August 14, 1883.

Application filed June 20, 1883. (No model.)

To all whom it may concern:

Be it known that I, JOSEPH BYRNES, a citizen of the United States, residing in the city of Chicago, in the State of Illinois, have invented certain new and useful Improvements 5 in Bottle-Stoppers, of which the following is the specification.

Figure 1 is a vertical section. Fig. 2 is a vertical sectional view with cap removed and 10 stopper inverted in the act of being removed. Fig. 3 is a vertical sectional view of cap and suspended stopper. Fig. 4 is a view of the stopper.

The nature and object of this invention is to 15 provide a cheap and serviceable bottle-stopper, as will hereinafter appear.

Similar letters of reference refer to similar parts in the different drawings.

A is a glass bottle having the neck B made 20 with shoulders *a* *b*, and terminating at the top without any bead.

C is a rubber washer on shoulder *b*.

D is a spiral spring around the neck and resting on shoulder *a*.

25 E is a metallic cap made sufficiently large to fit over the neck at its greatest diameter, and open at the top.

F is a cross-bar across the open top of cap, bent downwardly within the cap, and from 30 which hangs the hook H.

I is a rod suspended from hook H, and at its lower end is the stopper J, which is composed of the smaller washer, *d*, rubber packing *e*, larger washer, *f*, and extension *g*.

35 The operation of my improvement is as follows: The stopper J is inserted in the bottle through the neck, the rubber packing *e* folding over the smaller washer, *d*, until it passes into the bottle, when it returns to its natural 40 position. The cap is then placed in position, the rubber washer C and spiral spring D having been placed in position on the neck of the bottle. The spring D works between the shoulder *a* on the neck of the bottle and shoulder K in the cap. The bottle is then inverted and shaken, which causes the stopper J to take the position shown in Fig. 1, with the 45 rod I in the neck, when—the spring D being compressed—by the aid of a pair of nippers inserted through the open head of the cap, the

hook in the end of rod I is closed about the eye on hook H, suspended from cross-bar F, as shown in Fig. 1, when the spring D is permitted to react, and draws the stopper J snugly against the lower or inner end of neck 55 of bottle, and completes the stoppage of the bottle sufficiently tight to prevent the escape of fluids or gases. The stopper J can be first suspended from cross-bar F, and then pressed into position through the neck of the bottle, 60 if desired, the rubber packing *e* folding over the smaller washer, *d*, the same as just previously described.

To remove the stopper J a sharp-ended instrument—such as a screw-driver—is inserted 65 in the neck through the top of the cap, and with it the hook H is opened, as at *h*, Fig. 3. The cap is then pressed down and the bottle shaken, which causes the rod I to be disengaged from hook H. The cap B is then removed and the bottle inverted and shaken, 70 when the position of stopper J will be reversed. A pair of nippers is then inserted in the neck, and clasped on the extension *g* of the stopper J, and the stopper is removed from 75 the bottle, the rubber packing *e* folding over the smaller washer, *d*, as shown in Fig. 2.

The rubber washer C is a cushion for the shoulder *k* of the cap to strike against when it is pressed down; also, when filling the bottle, 80 the shoulder *k* is compressed against the washer C, which makes an air-tight joint, which prevents the escape of gas.

It will be observed that I have shown a 85 stopper which can be used in any kind of a bottle where repeated use is required—as in bottling beer, seltzer, and pop—and also in filling with highly-effervescent liquids, that can be removed when desired to clean the bottle, or otherwise, without injury to bottle or stopper, that will enable a portion of the highly-effervescent contents to be poured out, and the bottle to be immediately sealed, thus keeping the remaining portion in the bottle in a fresh 90 and active condition; and also it forms a perfectly tight joint while in the act of filling, and thus prevents the escape of gas.

I claim—

1. In combination with a bottle having the neck made with the shoulders *a* and *b*, the 95

rubber washer C, coiled spring D, cap E, having an open top, cross-bar F, and suspended stopper J, as and for the purpose shown.

2. The combination of the shoulder *b* on neck of bottle, rubber washer C, located on the shoulder, cap E, having an open top, and provided with shoulder K, and an internal stop-

per attached to the open cap, as and for the purpose set forth.

JOSEPH BYRNES.
